J. A. B. SMITH

TYPEWRITING MACHINE.

Original Filed Sept. 1st, 1920

Inventor:
Jesse A. B. Smith
by D. B. Stickney
Attorney

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Original application filed September 18, 1920, Serial No. 411,181. Divided and this application filed January 27, 1923. Serial No. 615,231.

To all whom it may concern:

Be it known that I, JESSE A. B. SMITH, a citizen of the United States, residing in Stamford, in the county of Fairfield and 5 State of Connecticut, have invented certain new and useful Improvements in Type-writing Machines, of which the following is a specification.

The present invention relates to collating 10 tables for typewriting machines. More particularly, the invention relates to tables on which sheets may be collated for so-called front insertion in front-strike typewriting machines; and to paper clips or fingers on 15 the table for holding the sheets in adjusted position during the collating operation.

The object of the invention is the provision 20 of a support for the fingers behind the table, and preferably on the rear face thereof, where the same cannot interfere with, or be disturbed by, the operator; and whence the fingers may be extended around the edge of the table to project into engagement with the front face thereof over the sheet-field.

25 A feature of the invention is a mounting, located as above, for the fingers, which permits a plurality of such fingers to be swung simultaneously to and from effective position, over a bar or flange forming a marginal, or side, gage, for the sheets at the 30 side of the table.

A further feature of the invention is a shaping of the fingers, and the formation thereof of spring sheet-material, such that, 35 after being thrown simultaneously to effective position and before being simultaneously released, each, independently of the other, may be lifted from the table for insertion of a sheet thereunder.

40 This application is a division of my application, Serial No. 411,181, filed September 18, 1920 (now Patent No. 1,451,791, granted April 17, 1923).

45 Other features and advantages will hereinafter appear.

In the accompanying drawings,

Figure 1 is a view of the platen and ac-

companying parts of the machine, showing the front collating table, and work-sheets in position thereon.

50 Figure 2 is a section taken on the line 2—2 of Figure 1.

Figure 3 is a section taken on the line 3—3 of Figure 2, and shows the means for rotating and holding the spring-clips on the collating table.

55 The platen 10 is journaled in the end walls 11 of the platen-carriage by means of a shaft 12, and is rotated by the ordinary knob 13. On the carriage is also the usual paper-table 15 having an apron extension 16, the latter being provided with openings 18 to accommodate the pressure-rolls 19. The printing position at the front of the platen is indicated by a type-bar 21; wing-scales 22 being shown at either side of the printing position.

60 A front collating table 30 is mounted in the end walls of the carriage by means of a shaft 32 passing through depending ears 31 on the table. The table is positioned tangentially to the front portion of the platen. One edge of the table is provided with an aligning bar or flange 35. Bent to the front face of the table, over the flange 35, are spring-clips 37 which terminate behind the table in upstanding portions 38, rigidly attached by means of screws 41 to a 65 shaft 39 which passes therethrough; the shaft 39 being journaled in brackets 40 fixed to the under side of the table. Rigidly attached to the shaft 39 is a collar 45, having two notches 46 and 47 in the periphery thereof, into which notches a detent-spring 49, fixed to the rear or under face of the table at 50, is adapted to fit. In the Figure 70 3 position of the parts, the spring-clips rest upon the table, and the detent 49, having its end in the notch 46, tends to hold the clips in this position. The detent 49 being resilient, however, the clips 37, and shaft 39 with the collar 45 thereon, may be

75 rotated, to bring the notch 47 to the detent 49, which latter, by springing into the notch 80 85 90 95

47, holds the shaft 39 and clips 37 in ineffective position, against unintentional angular displacement.

In operation, the pressure-rolls may be 5 released from the platen in the usual way, and the spring-clips thrown to ineffective position. The several work-sheets and carbons may then be adjusted with respect to each other, or collated, on the table, with 10 their lower or rear ends between the pressure-rolls and the platen; the spring-clips being thrown to effective position, temporarily to hold the collated sheets. The collation being completed, the pressure-rolls are 15 reapplied, clamping the sheets in their adjusted position to the platen. The spring-clips are then thrown to ineffective position to permit free movement of the collation to the first printing line, by turning the platen 20 in reverse direction, and then to permit line-space feed of the collation in the usual way during the writing. Certain sheets, such, for instance, as the record-sheet, may be fed under and around the platen, over the 25 table 15, in the usual way, to the table 30, before the other sheets are set upon and adjusted with relation to the sheets thus first inserted.

Variations may be resorted to within the 30 scope of the invention, and portions of the improvements may be used without others.

Having thus described my invention, I claim:

1. In a typewriting machine, a platen, a 35 collating table, and a paper-finger pivotally mounted behind the table, extending around the edge of the table, and projecting over the sheet-field at the front of the table, the finger being movable on its pivot into and 40 out of engagement with the front face of the table.

2. In a typewriting machine, a platen, a 45 collating table, a bar or flange on one side of the table to serve as a side gage for the paper, and a paper-finger pivotally mounted behind the table, extending around the edge of the table, over the side gage, and protruding laterally and downwardly over the sheet-field to the front face of the table, the 50 finger being movable on its pivot into and out of engagement with the front face of the table.

3. In a typewriting machine, a platen, a 55 collating table, a rock-shaft journaled on the rear of the table and parallel to the side edge thereof, a plurality of paper-fingers fast to the rock-shaft and spaced apart thereon; the fingers being bent around the side edge of the table to protrude laterally over the sheet-field into engagement with the front of the table, means for rocking the shaft to throw the paper-fingers into and out of engagement with the table, and means for 60 holding the shaft against unintentional rotary movement.

4. In a typewriting machine, a platen, a collating table, a rock-shaft journaled on the rear of the table and parallel to the side edge thereof, a plurality of paper-fingers fast to the rock-shaft and spaced apart 70 thereon; the fingers being bent around the side edge of the table to protrude laterally over the sheet-field into engagement with the front of the table, means for rocking the shaft to throw the paper-fingers into and out of engagement with the table, and a spring-detent engageable in notches in the shaft, to determine the finger-settings thereof and to prevent accidental rotary movement of the shaft from such settings. 80

5. In a typewriting machine, a platen, a collating table, a rock-shaft journaled on the rear of the table and parallel to the side edge thereof, a plurality of paper-clips fast to the rock-shaft and spaced apart thereon; the clips being bent around the side edge of the table to protrude laterally over the sheet-field into engagement with the front of the table, and means for rocking the shaft to throw the clips into and out of engagement with the table; the clips being resilient so that the same may be also independently pressed from the table. 90

6. In a typewriting machine, a platen, a 95 collating table, a rock-shaft journaled on the rear of the table and parallel to the side edge thereof, a plurality of paper-fingers fast to the rock-shaft and spaced apart thereon; the fingers being bent around the side edge of the table to protrude laterally over the sheet-field into engagement with the front of the table, means for rocking the shaft to throw the paper-fingers into and out of engagement with the table, a collar 100 on the rock-shaft having notches spaced apart on the periphery thereof, and a spring-detent secured to the rear face of the table and adapted to register with, and automatically enter, either of the notches, 105 upon proper rotary movement of the shaft, to hold the paper-fingers in the position to which they may be swung with the shaft. 110

7. In a typewriting machine, a platen, a 115 collating table, a bar or flange on the side of the table for gaging the side of the paper, a rock-shaft journaled on the rear of the table and parallel to the side edge thereof, a plurality of paper-fingers fast to the rock-shaft and spaced apart thereon; the fingers being bent around the side edge of the table, and around the side gage, to protrude laterally over the sheet-field into engagement with the front of the table, the shaft being rockable to throw the paper-fingers into and out of engagement with the table, and a yielding detent to hold said fingers against the table or away therefrom. 120 125

8. In a typewriting machine, a platen, a collating table, a rock-shaft journaled on the rear of the table, and a sheet-metal 130

paper-finger extending from the front of the table around the edge thereof, and, behind the table, having an ear bent at right angles thereto, and a hub on the ear to serve as a bearing for the finger on the rock-shaft.

5 on the shaft.

9. In a typewriting machine, a platen, a collating table, a rock-shaft journaled on the rear of the table, a sheet-metal paper-finger extending from the front of the table

around the edge thereof, and, behind the table, having an ear bent at right angles thereto, and a hub on the ear to serve as a bearing for the finger on the rock-shaft.

JESSE A. B. SMITH.
